UNITED STATES PATENT OFFICE.

CHARLES B. POST, OF NEW LONDON, OHIO.

DETACHABLE HANDLE.

No. 913,764.

Specification of Letters Patent.

Patented March 2, 1909.

Application filed February 1, 1908. Serial No. 413,753.

To all whom it may concern:

Be it known that I, CHARLES B. Post, a citizen of the United States, and resident of New London, county of Huron, State of Ohio, have invented certain new and useful Improvements in Detachable Handles, of which I hereby declare the following to be a full, clear, and exact description, such as will enable others skilled in the art to which 10 it appertains to make and use the same.

The objects of the invention are to provide means for detachably securing together a sleeve or socket portion and a central stem or rod closely fitting therein, and to so attach the parts together as to prevent rotation of one part on the other and I exemplify the invention in its adaption for use in securing a handle to an umbrella stem in which use it has many advantages. The 20 objects to be obtained in this use may be enumerated as follows: It permits of interchangeability of several styles of handles, and the removal of the handle if expensive when the frame and cover of the umbrella 25 are worn out, since an ornamental and costly handle will wear longer than several covers and frames and in this manner can be saved for future use. It is also useful in permitting separation of the handle from the frame 30 to engrave the handle.

Further advantages are found in the compactness of the article when removed for shipping or packing in trunks or suit cases and also the handle can be removed to prevent theft of the umbrella, since without 35 an ornamental handle the umbrella would lose much of its attractiveness.

Further objects of the device are to provide a shank or sleeve adaptable to all kinds 40 of handles which is simple in construction, so as to be easily operated by any one without danger of making mistakes or of injury to the umbrella, will preserve the full strength of the stem at the point of greatest 45 strain, can be attached and detached without removing the cover from the umbrella, can be easily operated with gloves on. Also the mode of operation is simple and there are no objectionable projecting parts or 50 hooks when the parts are separated.

The device is also durable, neat in appearance, and of slight initial cost, and has elements of increased efficiency and practicability in whatever uses it may be employed.

The invention consists primarily in outer

and inner telescoping portions and the spring catch or detent formed integrally in the outer portion or sleeve and a shoulder in the inner portion or stem, with added 60 means for releasing the catch readily accessible from the exterior of the outer sleeve.

The device by means of which the union is made comprises a socket piece adapted 65 for insertion in the umbrella handle. The outer end of the socket piece forms a sleeve which fits closely over the tubular stem of the umbrella.

To prevent detachment of the parts a 70 shoulder is formed in the side of the stem near its inner end, and a spring detent or catch is formed integrally from the wall of the sleeve and engages with this shoulder. To release the spring from the spring 75 catch a flattened pin is inserted in the spring catch and passes through the walls of the stem and sleeve and is terminated by a button or expanded part adapted to be easily pressed by the finger while grasping the 80 handle.

To permit of separating the parts, the pressure pin passes through open slots in the end of the stem, and the pin is made broad enough to find a firm bearing in the 85 slot, so as to prevent rotation and rattling of the parts.

The invention as illustrated in the accompanying drawings, is hereinafter described, and specifically pointed out in the claims. 90

In the accompanying drawings, Figure 1 is a longitudinal sectional view of the device; Fig. 2 is a face view of the inner end of the stem showing the slotted extremity thereof and the shoulder, on each side of the slot; 95 Fig. 3 is a similar view of the socket, showing the depressible button and the slot through which it passes; Fig. 4 is a view of the opposite side thereof showing the spring detent formed integrally out of the wall of 100 the sleeve and Fig. 5 is a side view of the extremity of the stem showing the shoulder cut from one side thereof through its wall. Fig. 6 is a vertical section showing a modified form; and Fig. 6^a is a detail of modified 105 pin.

In these views 1 is the umbrella stem, 2 the handle, which may be of any desired character, 3 is the socket piece which is provided with a shank portion, preferably of 110 the size of the stem where it enters the handle, and its outer end 4 is of requisite

size to form a sleeve fitting closely over the extremity of the stem. The wall of this sleeve is slotted longitudinally in parallel lines at 4', and transversely at 5, to form a tongue T which is separated therefrom on three sides but integral therewith at one end and is bent inwards at its tip 5'. The sleeve being made of tempered metal a spring detent is formed in this manner which is 10 adapted to engage the shoulder 6 cut in the wall of the stem, as soon as the stem is inserted in the sleeve socket 3.

The inner end of the stem abuts against the inner annular shoulder 7 in the sleeve at 15 the moment that the spring catch engages the shoulder 6 in the stem, so that the parts are rigidly locked together.

To depress the spring for the purpose of releasing the stem, a pin 8 is employed. 20 This pin extends through the open longitudinal slots 9 in the extremity of the stem and through a shorter slot 10 in the wall of the sleeve and projects beyond the sleeve so that its head 11 can readily be pressed by the 25 finger. The open slots 9 permit the pin to pass out of the stem when the spring is released and the pin is broadened to form a firm bearing surface and to prevent rotating the parts on each other.

30 In use the handle can be grasped in one hand and the stem in the other. The spring can then be depressed easily to detach the parts so that the handle and sleeve can be pulled away from the stem.

35 Fig. 6 shows a sectional view of a modified form of pin and Fig. 6^a is a detail of the same.

Having described the invention what I 40 claim as new and desire to secure by Letters Patent is:—

1. In combination, with a socket piece, comprising, shank and sleeve portions, a stem adapted for insertion in said sleeve, a spring detent cut integrally from the wall of 45 the sleeve and turned inwardly at its tip, a shoulder in the stem which said spring detent is adapted to engage when the parts are brought together and means for releasing said spring accessible from the exterior surface of said sleeve, said releasing means forming also means to prevent the rotation 50 of one part on the other.

2. The combination with a socket piece, comprising, shank and sleeve portions, of a stem insertible in said sleeve, a shoulder in 55 said stem, and a spring portion formed integrally in the wall of the sleeve, said spring forming a detent operatively connected therewith and adapted to engage with said shoulder in said stem when the parts are brought 60 together, and a pin adapted to pass through the walls of said sleeve and stem and attached to said spring, said stem being longitudinally slotted at its extremity in both sides to permit of the free movement of said 65 pin when the parts are separated.

3. The combination with a socket piece, comprising, shank and sleeve portions, of a stem insertible in said sleeve portion a shoulder on said stem, a tongue forming a 70 spring detent, operatively connected with the wall of said sleeve, said sleeve provided with longitudinal and transverse incisions adapted to separate said tongue therefrom on sides and end, said tongue adapted to engage said shoulder when the parts are assembled, a shoulder in the sleeve against which said stem abuts, a depressible pin extending through the walls of said sleeve and stem and connected with said spring tongue, the 75 walls of said stem being longitudinally slotted to permit the withdrawal thereof when the spring is released.

4. The combination with a stem and sleeve thereon, of an integral spring detent in said sleeve, adapted to make engagement with said stem, and an operating pin for said spring said pin adapted to prevent rotation of said parts upon each other.

5. The combination with telescoping sections, of a spring detent out of contact with the body of the outer section on three sides and integrally attached thereto, a shoulder in the inner section adapted to normally engage said spring detent, and a releasing means for said spring, said releasing means forming a means for preventing the rotation of one part on another.

In testimony whereof I hereunto set my hand this 26th day of January, 1908.

CHARLES B. POST.

In presence of—
E. M. PALMER,
R. L. JOHNSON.
